UNITED STATES PATENT OFFICE

JAMES A. CAMERON, OF BROOKLYN, NEW YORK, ASSIGNOR TO CAMERON MACHINE COMPANY, OF BROOKLYN, NEW YORK, A CORPORATION OF NEW YORK

SLITTING DEVICE

Application filed September 7, 1929. Serial No. 391,015.

This invention relates generally to slitting devices, and has more particularly reference to score-cut slitting devices to divide a web of flexible material into longitudinal sections.

One of the difficulties encountered in the art of slitting a web of flexible material is the vibration, due to the high speed of modern slitting machines, of slitting members. The effect of such vibration is to cause, at times, a chattering of the slitting element with respect to the backing roller, a deviation of the cutter from a straight line and a reluctance of the cutting element to equal the high speed of the flowing web. These difficulties can be largely traced to undue heaviness, in proportion to other parts, of the slitting element, and the main object and feature of the invention is to lessen the weight of the slitter mounting, to insure free rotation of the slitting element at high speeds while at the same time steadyng said element to thereby prevent it from leaving its straight path or trace.

In the accompanying drawings, the invention is disclosed in a concrete and preferred form in which:

Fig. 1 is a transverse sectional view through a backing roller and support for a slitting cutter, showing the latter and its carrier and cutter holder in elevation;

Fig. 2 is a fragmentary view in elevation looking in the direction of arrow 2 of Fig. 1; and

Fig. 3 is a sectional detail view substantially on the plane of line 3-3 of Fig. 1.

1 indicates a backing roller having a "glass-hard" surface and 2 is a score-cutter coacting therewith. Said score-cutter is rotatably mounted at 3 in cutter holder 4, which latter is pivotally supported at 5 on carrier 6. Carrier 6 is adjustably mounted on support 7, and by means of this latter, said support being a rockshaft, the carrier is movable toward and away from the backing roller.

It will be observed that the cutter holder is pivoted adjacent to its lower end and that it carries the bearings indicated by 3 adjacent its upper end. Also that said cutter holder has what may be called an abutment surface, indicated at 8, which is substantially in the plane of slitting and on that side of

the score-cutter that faces away from the backing roller. 9 indicates a spring member exerting its thrust substantially in the direction of a line (indicated by 10) that passes through the centers of the backing roller and score-cutter. This spring is mounted in a bracket 11 and is secured thereto by set-screw 12. Said bracket is pivotally supported at 13 on carrier 6 and is held by a pivotally supported bolt 14 and wing nut 15. It will be seen that the thrust of the spring member is directly against abutment surface 8 and is substantially in the plane of slitting.

Preferably the cutter holder is a segmental-shape piece of sheet material formed into a cup-like member and provided at its lower end with a bushing 16 that rocks on pivot 5 of the carrier. Said bushing may be welded to the sheet material member, and may be provided with a stop 17 to engage pin 18 of the carrier. As here shown, the sheet material member is conveniently provided with pressed-out bearings 3 that receive anti-friction bearings 19, the inner race, 20, of which is rigidly connected to studs 21. 22 is a shaft, here shown hollow, to the interior of which the studs are rigidly connected. On the exterior of this shaft is rigidly mounted score-cutter 2 and also two steadyng member 23 and 24 that clamp or elasp opposite sides of the score-cutter. Member 23 can conveniently be welded to the shaft as indicated at 25, and member 24 can be in threaded engagement with the shaft so that, by adjustment, the score-cutter can be adequately clamped. If desired, a wick 26 leading from a water or oil receptacle can be led from the carrier up through an opening in the cutter holder. It is obvious that the feature requisite for the slitter holder can be obtained by the use of thin-wall castings preferably made of a metal combining lightness and strength such as an aluminum alloy.

It will be seen from the foregoing, that the spring member exerts its thrust very directly and also that the cutter holder is of very light construction and therefore does not create a perceptible rebound; furthermore, shaft 22 is of ample proportions in relation to the thickness of the cutter, the steadyng mem-

bers engage said cutter at a point well toward its periphery, and bearings 3 are spaced an appreciable distance apart.

The result of the above construction is that great steadiness of the cutter is obtained, and that said cutter is capable of rotating at very high speeds without rebound or vibration, the direct thrust of the spring also tending to keep the cutter in a straight trace.

10 I claim:

1. A slitting device including: a backing roller, a score-cutter to coact therewith, a cutter holder rotatably supporting the score-cutter, a carrier pivotally supporting the cutter holder, and a spring member, anchored on the carrier and exerting its thrust against the cutter holder substantially in the direction of a line that passes through the centers of the backing roller and score-cutter, to urge said score-cutter toward the backing roller.

15 2. A slitting device including: a backing roller, a score-cutter to coact therewith, a cutter holder rotatably supporting the score-cutter, a carrier movable toward and away from the backing roller and pivotally supporting the cutter holder, and a spring member, anchored on the carrier and exerting its thrust against the cutter holder substantially in the direction of a line that passes through the centers of the backing roller and score-cutter, to urge said score-cutter toward the backing roller.

20 3. A slitting device including: a backing roller, a score-cutter to coact therewith, a cutter holder rotatably supporting the score-cutter, a carrier movable toward and away from the backing roller, a pivotal support at the upper end of the carrier on which the cutter holder is pivotally mounted, a spring member anchored on the carrier below the pivotal support and extending above the same into engagement with the cutter holder to thereby press the score-cutter against the backing roller.

25 4. A slitting device including: a backing roller, a rotatable score-cutter to coact therewith, a pivotally supported cutter holder having an abutment located in the plane of slitting on that side of the score-cutter that faces away from the backing roller, a carrier, movable toward and away from the backing roller, to pivotally support the cutter holder, and a spring member anchored on the carrier to engage said abutment to thereby press the score-cutter against the backing roller.

30 5. A mounting for a slitting member including: a cutter holder, spaced-apart bearings on said cutter holder, a shaft rotatably mounted at each end in the bearings of said cutter holder, a slitting cutter mounted to rotate with the shaft, and steadyng members also mounted to rotate with the shaft and clamping opposite sides of the slitting cutter.

35 6. A mounting for a slitting member in-

cluding: a cutter holder pivotally supported adjacent its lower end, spaced-apart bearings on said cutter holder, adjacent its upper end, a shaft rotatably mounted at each end in the bearings of said cutter holder, a score-cutter mounted to rotate with the shaft, steadyng members also mounted to rotate with the shaft and clamping opposite sides of the score-cutter, a rotatable backing roller to coact with the cutter, and a spring member to urge the score-cutter toward the backing roller.

40 7. A slitting device including: a backing roller, a pivotally supported cutter holder, two spaced-apart bearings on the cutter holder, a rotatable score-cutter mounted in said bearings, a carrier, movable toward and away from the backing roller, to pivotally support the cutter holder, and a spring member anchored on the carrier, to press the score-cutter against the backing roller, located intermediate the bearings, substantially in the plane of slitting, and exerting its thrust against the cutter holder and in the direction of the backing roller.

45 8. A slitting device including: a backing roller, a rotatable score-cutter to coact therewith, a pivotally supported cutter holder having an abutment located in the plane of slitting on that side of the score-cutter that faces away from the backing roller, a carrier, movable toward and away from the backing roller, to pivotally support the cutter holder spaced-apart bearings on the cutter holder to rotatably support the score-cutter therebetween, and a spring member anchored on the carrier to engage said abutment to thereby press the score-cutter against the backing roller.

50 9. A slitting device including: a backing roller, a score-cutter to coact therewith, a cutter holder rotatably supporting the score-cutter, a carrier movable toward and away from the backing roller, a support on the carrier to pivotally sustain the cutter holder, and a spring member anchored on the carrier and extending across the pivotal support into engagement with the cutter holder to thereby press the score-cutter against the backing roller when said spring member is placed under tension by that movement of the carrier which brings the score-cutter into engagement with the backing roller.

55 10. A slitting device including: a backing roller, a rotatable score-cutter to coact therewith, a pivotally supported cutter holder having an abutment located in the plane of slitting on that side of the score cutter that faces away from the backing roller, a carrier movable toward and away from the backing roller, to pivotally support the cutter holder, and a spring member anchored on the carrier and extending across the pivotal support to engage said abutment to thereby press the score-cutter against the backing roller when

said spring member is placed under tension by that movement of the carrier which brings the score cutter into engagement with the backing roller.

5 11. A slitting device including: a backing roller, a carrier movable toward and away from the backing roller, a cutter holder pivotally supported on the carrier, a shaft extending parallel to the pivotal support of the cutter holder, spaced-apart bearings on the cutter holder to rotatably support the shaft, a score-cutter mounted on the shaft intermediate the ends of the latter and in spaced relation to the bearings, steadyng 10 members, also mounted to rotate with the shaft, located intermediate the bearings and the score-cutter and clamping opposite sides of said score-cutter, and a spring member to urge the cutter holder toward the backing 15 roller.

20 12. A mounting for a slitting member including: a cutter holder of sheet material, spaced-apart bearing sockets formed in said cutter holder, a shaft rotatably mounted at each end in the bearing sockets of said cutter 25 holder, a slitting cutter mounted to rotate with the shaft, and steadyng members also mounted to rotate with the shaft and clamp- ing opposite sides of the slitting cutter.

30 Signed at the city of New York, in the borough of Brooklyn, county of Kings, and State of New York, this 29 day of August, 1929.

JAMES A. CAMERON.
